CLAIM

The ornamental design for a cutting board as shown and described.

DESCRIPTION

FIG. 1 is a first perspective view of a cutting board showing my new design;

FIG. 2 is another perspective view thereof;

FIG. 3 is a top view thereof;

FIG. 4 is a front view thereof;

FIG. 5 is a bottom view thereof;

FIG. 6 is a right side view thereof, the left side being a mirror image thereof;

FIG. 7 is an environmental view thereof holding a knife in a sink; and,

FIG. 8 is an exploded view thereof showing the removal of the plug, spacer, and magnets visible during replacement. The broken lines are for the purpose of illustrating environmental structure and form no part of the claimed design.
